(57) **CLAIM**

The ornamental design for a low profile end loaded folded dipole antenna, as shown and described.

DESCRIPTION

FIG. 1 is a top perspective view of a low profile end loaded folded dipole antenna.

FIG. 2 is a top plan view of the low profile end loaded folded dipole antenna of FIG. 1.

FIG. 3 is a bottom plan view of the low profile end loaded folded dipole antenna of FIG. 1.

FIG. 4 is a side view of the low profile end loaded folded dipole antenna of FIG. 1.

FIG. 5 is a side view of the low profile end loaded folded dipole antenna of FIG. 1.

FIG. 6 is a front view of the low profile end loaded folded dipole antenna of FIG. 1; and,

FIG. 7 is a rear view of the low profile end loaded folded dipole antenna of FIG. 1.
